(57) **CLAIM**

The ornamental design for a lithium battery as shown and described.

DESCRIPTION

1. Lithium battery

1.1 : Front

1.2 : Back

1.3 : Left

1.4 : Right

1.5 : Top

1.6 : Bottom

1.7 : Perspective

The broken lines in the drawings are for the purpose of illustrating portions of the article that form no part of the claimed design.

1 Claim, 7 Drawing Sheets
